(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface, showing the graphical user interface of FIG. 3 applied to a display screen or portion thereof;

FIG. 2 is a second embodiment thereof; and,

FIG. 3 is a front view of an electronic device with graphical user interface. The graphical user interface design of FIG. 2 may be similarly applied thereto.

The broken lines in FIGS. 1 and 2 show a display screen or portion thereof, and form no part of the claimed design. The broken lines in FIG. 3 show an electronic device having a display screen, and form no part of the claimed design.
